[57] **CLAIM**

The ornamental design for a display package, substantially as shown.

DESCRIPTION

FIG. 1 is a perspective view of a display package showing our new design;

FIG. 2 is a front elevational view;

FIG. 3 is a top plan view;

FIG. 4 is a bottom plan view;

FIG. 5 is a side elevational view; and

FIG. 6 is a rear elevational view thereof.

The side elevational view opposite to that shown in FIG. 5 is a mirror image of the side elevation illustrated in FIG. 5.

FIG. 1.FIG. 2.FIG. 3.FIG. 4.FIG. 5.FIG. 6.
